UNITED STATES PATENT OFFICE.

JAN NEŠETŘIL, OF PRAGUE, AUSTRIA-HUNGARY, ASSIGNOR TO JOSEPH PRINCE
COLLOREDO-MANNSFELD, OF DOBRIS, AUSTRIA-HUNGARY.

APPARATUS FOR MIXING CEMENT AND FIBROUS MATERIAL.

1,138,397.

Specification of Letters Patent.

Patented May 4, 1915.

Application filed March 6, 1914. Serial No. 822,982.

To all whom it may concern:

Be it known that I, JAN NEŠETŘIL, citizen of the Austro-Hungarian Empire, residing at Prague, II, Austria-Hungary, have invented certain new and useful Improvements in Apparatus for Mixing Cement and Fibrous Material, of which the following is a specification.

This invention relates to an apparatus for mixing cement and fibrous material such as asbestos, for use in the molding of railway sleepers and other articles.

The object of the invention is to insure a proper reduction of the fibrous material and a thorough intermingling of the reduced fiber with the pulverized or powdered cement, first in the dry state and then with the addition of water, and to enable these operations to be carried out by and in the same apparatus with efficiency and economy.

With these objects in view the invention consists in the combination of parts herein-after referred to and set forth in the claims. In the accompanying drawings:—Figures 1 and 2 are respectively a sectional front elevation and a sectional side elevation of one form of apparatus according to the invention.

The form of apparatus illustrated comprises a spiked drum 25 rotatably mounted in a casing 24, and a stationary cover or roof 26 provided with spikes between which and the spikes on the drum the asbestos is torn or reduced to small pieces or fibers. Adjacent to the drum and forming part of the casing 24 is a store compartment 27 for the pulverized cement, a conveying roller 28, arranged at the lower end of the said compartment conveying the cement into the path of the fibers falling down from the drum 25. At a point where the fibers and the cement meet, a pair of rollers 29, 30 are revolvably mounted. These rollers are provided with a series of grooves in such a manner that the points of the grooves of one roller engage the corresponding grooves of the other roller. Moreover, the smaller roller 30 rotates at a greater speed than the larger roller 29 and in this way and by these means the asbestos fibers and the cement are subjected to a primary mixing and the fibers are combed or made to lie parallel to each other. Below the rollers 29, 30 is a funnel 40 which leads the mixture into a secondary mixing device comprising a main casing 24

in which there is a second smaller casing 31 of substantially cylindrical shape and rotatably mounted therein a drum 32 carrying a number of plates 33 of triangular section having openings at their sides. A hollow driving shaft 35 is adapted to convey water into the triangular plates by means of tubes 34 which communicate therewith and with the shaft 35, and the drum 32 serves therefore to allow of the admission of water into the asbestos-cement mixture during the secondary mixing operation. Alternately mounted between the plates 33 and on the circumference of the drum 32 and partly within recesses provided therein are rollers 36 the axles of which carry on one side toothed wheels 37. All of these toothed wheels mesh with a stationary large toothed wheel 38 so that the rollers 36, upon the rotation of the drum 32, are caused to rotate not only around their own axes but also around that of the said drum, thus effecting a thorough secondary mixture and uniform moistening of the asbestos and cement. The resulting mixture is now caused to drop into a funnel 41 secured at the bottom of the casing 31 whence it falls between two rollers 39 and finally into a charge or filling box 47.

The upper funnel 40 mounted at the top of the casing for the reception and guidance of the falling asbestos and cement, and the lower funnel 41 are provided with slides 42 and 43 respectively, in order that the corresponding inlets to and outlets from the casing may be shut off when so desired.

To convey the mixture of asbestos and cement provision is made on the base 44 of the main casing 24 of a small rail track 45. A wagon or truck 46 preferably having rubber tires is adapted to carry the filling box or mold 47, which in the particular form illustrated is shaped to mold a railway sleeper and is provided with cores 50 carried by plates 48 to form recesses in the sleeper for retaining bolts.

I claim:—

1. Apparatus for mixing cement and fibrous material, comprising, primary mixing means consisting of intermeshing grooved rollers and means for delivering fibrous material and dry cement thereto, secondary mixing means for receiving dry mixture from the said primary mixing means, and for subjecting said mixture to a further treatment, means for supplying

- water to said secondary mixing means, and means for discharging the resulting wet mixture substantially as hereinbefore set forth.
- 5 2. Apparatus for mixing cement and fibrous material, comprising means for reducing fibrous material, a hopper for pulverized cement, primary mixing means for mixing the reduced fibrous material and the said cement and for combing the fibrous material, secondary mixing means, and means for supplying water to said secondary mixing means substantially as and for the purpose hereinbefore set forth.
- 10 15 3. Apparatus for mixing cement and fibrous material, comprising a spiked roller and a spiked surface in fixed relation thereto, for reducing the fibrous material, a hopper for pulverized cement, a pair of intermeshing grooved rollers below said spiked roller and hopper for subjecting the fibrous material and cement to a primary mixing, secondary mixing means, a funnel for conveying the primarily mixed fibrous material and cement 20 from the aforesaid rollers to the said secondary mixing means, and means for supplying
- 25

water to said secondary mixing means substantially as and for the purpose hereinbefore set forth.

4. Apparatus for mixing cement and fibrous material, comprising, primary mixing means for mixing fibrous material and cement in the dry state, a funnel for discharging the dry mixture to secondary mixing means said secondary mixing means consisting of two concentric casings, the larger being stationary and the smaller being rotatable, hollow perforated plates on said rotary casing, a hollow shaft for said rotary casing, tubes connecting said shaft with the aforesaid hollow plates for conveying water thereto, and rollers carried by the rotary casing, and means for rotating said rollers about their own axes, substantially as and for the purpose hereinbefore set forth. 40 45

In testimony whereof I have signed my name to this specification in the presence of two subscribing witnesses.

JAN NEŠETŘIL.
